UNITED STATES PATENT OFFICE.

JOHN P. SCHUUR, OF KALAMAZOO, MICHIGAN.

DUMB-BELL.

Application filed July 13, 1922. Serial No. 574,602.

To all whom it may concern:

Be it known that I, JOHN P. SCHUUR, a citizen of the United States, residing at the city and county of Kalamazoo, State of Michigan, have invented certain new and useful Improvements in Dumb-Bells, of which the following is a specification.

This invention relates to improvements in dumb bells.

10 The main object of this invention is to provide an improved dumb bell, the weight of which may be very considerably varied and one which at the same time is neat and attractive in appearance.

15 Further objects, and objects relating to structural details, will definitely appear from the detailed description to follow.

I accomplish the objects of my invention by the devices and means described in the 20 following specification. The invention is clearly defined and pointed out in the claims.

A structure which is a preferred embodiment of my invention is clearly illustrated in the accompanying drawing, forming a 25 part of this application, in which:

Fig. I is a side view of a dumb bell embodying the features of my invention.

Fig. II is an enlarged detail partially in 30 longitudinal section on a line corresponding to line 2—2 of Figs. I, III and IV.

Fig. III is a transverse section on a line corresponding to line 3—3 of Figs. I and II.

Fig. IV is an end view of one of the casting members.

35 In the drawing similar reference characters refer to similar parts throughout the several views and the sectional views are taken looking in the direction of the little arrows at the ends of the section lines.

40 Referring to the drawing, the hand bar portion 1 in the structure illustrated is a bar of uniform dimensions although this may be shaped up as desired. The hand bar is provided with a shank portion 2 of non-circular cross section and having a collar 3 at its inner end.

I provide a spherical casing, the hemispherical sections 4 and 5 being provided with rabbeted edges forming an interlapping 50 joint, designated generally by the numeral 6. The inner section 4 has an exterior recess 7 adapted to receive the collar 3. The outer section 5 has a recess 8 adapted to receive the clamping nut 9 threaded upon the end of 55 the spindle 2. These casing sections are pro-

vided with inwardly projecting annularly disposed lugs 10.

I provide a plurality of disk-like weights 11 each having groove-like recesses 12 in the periphery thereof adapted to receive the lugs 60 of the casing members so that the parts may be engaged with a relative rotative movement. These disks 11 are preferably of varying thickness, thereby securing a greater variation in the weight of the dumb bell as 65 one or more of these disks are removed. The disks have non-circular central holes 13 in the non-circular cross section, so that when the weights are mounted thereon they are supported against rotation. 70

In assembling the inner casing section is placed upon the handpiece, the weighting disk may be inserted and the parts relatively rotated, thereby bringing the lugs into engaging relation with the weights and the 75 parts properly assembled may be slipped upon the non-circular portion of the shank and clamped thereto.

I have illustrated and described my improvements in an embodiment which I consider very practical. I have not attempted to conform to accepted standards in the matter of proportion of parts considered, but it will be understood that they may be greatly varied as circumstances may require. 80 85

Having thus described my invention, what I claim as new and desire to secure by Letters Patent, is:

1. In a structure of the class described, the combination of a bar provided with a shank of non-circular cross section and having a collar at its inner end, a casing comprising a pair of hemi-spherical sections removably mounted on said shank, said casing sections being provided with internal annularly disposed lugs, a plurality of disk-like weights having peripheral recesses engageable with said lugs by a rotative movement of the weights with the casing members, said weights being engageable with the 90 said shank whereby they are non-rotatably supported, and a nut threaded upon said shank clamping said casing against said collar. 95

2. In a structure of the class described, the combination of a bar provided with a shank of non-circular cross section, a casing comprising a pair of hemi-spherical sections removably mounted on said shank, said casing sections being provided with internal 100 110

annularly disposed lugs, a plurality of disk-like weights having peripheral recesses engageable with said lugs by a rotative movement of the weights with the casing members, said weights being engageable with the said shank whereby they are non-rotatably supported.

3. In a structure of the class described, the combination of a hand bar, a casing comprising a pair of hemi-spherical sections removably mounted on said bar, said casing sections being provided with internal annularly disposed lugs, a plurality of disk-like weights having peripheral recesses engageable with said lugs by a relative rotative movement of the weights and the casing members, and means for removably and non-rotatably securing said parts upon said bar.

4. In a structure of the class described, the combination with a bar, a spherical casing comprising complementary sections, said casing being provided with internal annularly disposed lugs, a plurality of weights having peripheral recesses adapted to be engaged with said lugs by relative rotative movement, said weights being removably engaged with said bar and non-rotatably supported thereby, and means for removably securing said casing members with the weights therein upon said bar.

5. In a structure of the class described, the combination with a bar, a spherical casing comprising complementary sections, said casing being provided with internal lugs, a plurality of weights adapted to be engaged with said lugs by relative rotative movement, said weights being non-rotatably supported by said bar, and means for securing said casing members with the weights therein upon said bar.

6. In a structure of the class described, the combination with a bar, a sectional casing provided with internal lugs, a plurality of weights adapted to be engaged with said lugs by relative rotative movement, said weights being removably engaged with said bar, and non-rotatably supported thereby, and means for removably securing said casing with the weights therein upon said bar.

7. In a structure of the class described, the combination with a bar, a sectional casing provided with internal lugs, a plurality of weights adapted to be engaged with said lugs by relative rotative movement, said weights being non-rotatably supported on said bar.

In witness whereof, I have hereunto set my hand and seal.

JOHN P. SCHUUR. [L.S.]
